SHEET METALWARE PRODUCTION

George M. Ambrosius, Lakewood, Ohio, assignor
to The Standard Oil Company (Ohio), Cleve-
land, Ohio, a corporation of Ohio

Application April 29, 1936, Serial No. 76,912

11 Claims. (Cl. 153—21)

This invention relates to sheet metal ware production, and it is among the objects of the invention to provide for special indenting of the edge of headed sheet metal containers, such as grease cartridges, etc. Other objects and advantages will appear as the description proceeds.

To the accomplishment of the foregoing and related ends, the invention, then, comprises the features hereinafter fully described, and particularly pointed out in the claims, the following description and the annexed drawings setting forth in detail certain illustrative embodiments of the invention, these being indicative however, of but a few of the various ways in which the principle of the invention may be employed.

In said annexed drawings:—

Fig. 1 is a plan view of die mechanism embodying the invention; Fig. 2 is a vertical section thereof taken on a plane substantially indicated by line II, Fig. 1; Figs. 3 and 4 are front and rear elevational views respectively; Fig. 5 is a vertical sectional view taken on a plane substantially indicated by line V—V, Fig. 1, that is the work support is removed; Fig. 6 is a similar view showing the die in closed position; Fig. 7 is an enlarged sectional view similar to Fig. 2, showing the work piece in position and in process of die action; and Fig. 8 is an end view of the work piece or product as completed.

Referring more particularly to the drawings, there is shown a die comprising a die head or block 2 held by suitable means, as screws 3 to the support 4. Mounted in the die head or block is a set of die elements 5 which are radially movable and may be in the form of slide-elements riding in corresponding guide-ways in the die head and arranged to expand to engage the inner periphery of the end of a depressed headed container C, Fig. 7. Coacting with the die elements 5 is another set of outer die elements 8 mounted in reciprocable condition whereby to move radially, as for instance in guideways in the die elements 5 and die head. The outer periphery of the internal die elements 5 have one or more die-recesses 9, and the inner periphery of the outer die elements 8 have a corresponding set of die-projections 10, whereby to indent or upset inwardly a narrow portion of the headed end of the sheet metal container C, the number of such indentations produced depending upon the particular number or configuration desired, the illustration showing three equi-spaced indentations d, Fig. 8. A retaining ring 12 held to the die block by suitable means, as screws 13, serves to retain the movable sets of die elements

while allowing their radial reciprocative movements. Convenient means for automatically separating the inner and outer sets of die elements 5 and 8 is provided, and this may be for instance in the form of a spring 14 interposed in a suitable recess and more or less housed between the elements 5 and 8. With such arrangement, the inner and outer dies are normally separated, as shown in Figs. 2 and 5. For actuating or moving the inner die elements 5 radially outwardly, a suitable spreading or thrusting means is provided, and this may take the form for instance of a tapered plunger 15 which is reciprocable centrally of the die elements 5 to expand them to their outward position, and such plunger may be reciprocated by suitable means, as for instance the wedge element 16 carried by die plate 17, and being reciprocably movable therewith by suitable reciprocative press means the details of which are immaterial, it being understood that the die plate 17 may be secured by its stud 18 to a suitable reciprocating member of a press, mechanical or hydraulic or the like, and the other die member 4 is secured to the other jaw of such press. For returning the spreading plunger 15, suitable means are provided, preferably an automatic means, as for instance a spring 20 on a stem extension 21, the spring being arranged between the shoulder 22 of the die member and a collar 23 on the stem 21. To limit the back movement of the stem 21 and the plunger 15, a stop 24 may be secured to the die member by suitable means, for instance screw 25. With such arrangement, the inner die members 5 are spread or moved radially outwardly when the plunger 15 is thrust against them by the wedge 16, on the downward movement of the die plate 17, while on the upward movement of the latter the spring 20 draws the plunger 15 back and allows the die members 15 to contract.

Arranged to cooperate with the movement of the inner die members 5, is a suitable means for moving the outer die elements 8, and conveniently this may take the form of cam operating means, such as an annular member 28 having cam races 29 bearing on the outer die elements 8, the latter having suitably contoured coacting faces. The cam annulus 28 is conveniently also mounted in position by the retaining ring 12, the cam annulus being suitably shouldered as at 30 therebehind, such as to prevent disassembly but allow of rotary or oscillating movement of the cam annulus as mounted by the retaining ring. For oscillative movement of the cam annulus a laterally projecting arm 31 is arranged to receive rocking

movement by suitable means, for instance a link 32 mounted on the die plate 17 and being reciprocable therewith. Desirably, a small amount of lost motion is permitted, for instance by a connection through slot 33 in the link and pin 34 on the arm 31. With this, the operation of the respective portions of the die mechanism can be suitably timed, the wedge element 16 beginning its operation of expanding the inner die elements suitably in advance of the closing of the outer die elements.

The general operation will be understood from the foregoing. With the die open or in the position shown in Fig. 2, the operator sets a blank 15 on the work support 36, this being of suitable holding form, for instance trough-like, as shown more fully in the end view Fig. 3. The blank comprises a sheet metal tubular body 37 and a depressed head 38 flanged together. With the edge thereof in position against the die block 2 and the die plate 17 coming into reciprocative movement, the wedge member 16 is thrust against the spreading plunger 15 which thereupon spreads the radially-movable inner die elements 20 5 to their outer position against the inner periphery of the depressed container-head 38, as seen in Fig. 7. With the internal die elements 5 thus in position against the work-piece, the further descent of the die plate 17 causes the link 30 32 to rock the arm 31 and thereby oscillate the cam annulus 28, whereupon the cam races 29 force the outer die elements 8 to their inner or closed position, and the die projections 10 thereof thrust inwardly against the periphery of the 35 end of the work piece and force the metal thereof into the die recesses 9 of the internal dies, thereby forming the indents *d* as shown in Fig. 8. With the raising of the die plate 17, the cam annulus 28 is turned and the cam races thereof 40 moved away from the external die elements 8, and the wedge member 16 withdraws from the spreading plunger 15, allowing the spring 20 to pull the latter back, and spring means 14 spreads and opens the die couple, whereupon the completed work C is withdrawn by the operator 45 and a new blank substituted, and the operation repeated, etc.

Other modes of applying the principle of the invention may be employed, change being made 50 as regards the details described, provided the features stated in any of the following claims, or the equivalent of such, be employed.

I therefore particularly point out and distinctly claim as my invention:—

55 1. In mechanism of the character described, a die block, internal die elements radially expandible to engage the inner periphery of the end of a depressed headed sheet metal container, three equi-spaced outwardly directed narrow die recesses in said die elements, a tapered plunger reciprocable centrally of said die elements to expand the same, a wedge member reciprocable transversely to operate said tapered plunger, spring means for withdrawing said tapered plunger when said wedge member is in its remote position, outer die elements movable radially to close in on the outside of the headed container opposite said first-named die elements, die projections on said outer die elements to mate with the outwardly directed die recesses on said inner die elements, spring means for separating the outer and inner die elements, an annular member with internal cam races bearing on said outer die elements, an arm projecting laterally from said member, a link and a lost motion pin and slot connection between said link and said arm, actuating means in common connected to said link and the aforementioned wedge member, a retaining ring forwardly of said movable die elements, and a work support forwardly thereof.

2. In mechanism of the character described, a die block, internal die elements radially expandible to engage the inner periphery of the end of a depressed headed sheet metal container, outwardly directed narrow die-recess means in said die elements, a tapered plunger reciprocable centrally of said die elements to expand the same, a wedge member reciprocable transversely to operate said tapered plunger, spring means for withdrawing said tapered plunger when said wedge member is in its remote position, outer die elements movable radially to close in on the outside of the headed container opposite said first-named die elements, die projections on said outer die elements to mate with the outwardly directed die recesses on said inner die elements, 5

10 spring means for separating the outer and inner die elements, an annular member with internal cam races bearing on said outer die elements, an arm projecting laterally from said member, a link and a lost motion pin and slot connection 15 between said link and said arm, actuating means in common connected to said link and the aforementioned wedge member, a retaining ring forwardly of said movable die elements, and a work support forwardly thereof. 20

3. In mechanism of the character described, internal die elements radially expandible to engage the inner periphery of the end of a depressed headed sheet metal container, outwardly directed narrow die-recess means in said die elements, a tapered plunger reciprocable centrally of said die elements to expand the same, a wedge member reciprocable transversely to operate said tapered plunger, spring means for withdrawing said tapered plunger when said wedge member is in its remote position, outer die elements movable radially to close in on the outside of the headed container opposite said first-named die elements, die projections on said outer die elements to mate with the outwardly directed die recesses on said inner die elements, 25 spring means for separating the outer and inner die elements, an annular member with internal cam races bearing on said outer die elements, an arm projecting laterally from said member, a link and a lost motion pin and slot connection 30 between said link and said arm, actuating means in common connected to said link and the aforementioned wedge member, a retaining ring forwardly of said movable die elements, and a work support forwardly thereof. 35

4. In mechanism of the character described, a die block, internal die elements radially expandible to engage the inner periphery of the 40

end of a depressed headed sheet metal container, outwardly directed narrow die-recess means in said die elements, a tapered plunger reciprocable centrally of said die elements to expand the same, a wedge member reciprocable transversely to operate said tapered plunger, spring means for withdrawing said tapered plunger when said wedge member is in its remote position, outer die elements movable radially to close in on the outside of the headed container opposite said first-named die elements, die projections on said outer die elements to mate with the outwardly directed die recesses on said inner die elements, 45 spring means for separating the outer and inner die elements, an annular member with internal cam races bearing on said outer die elements, an arm projecting laterally from said member, a link and a lost motion pin and slot connection 50 between said link and said arm, actuating means in common connected to said link and the aforementioned wedge member, and a work support forwardly thereof. 55

5. In mechanism of the character described, a die block, internal die elements radially expandible to engage the inner periphery of the 60

for inwardly offsetting spaced portions of the extending free end edge of the depressed headed sheet metal container, including outwardly directed narrow die-recess means in said internal die elements, outer die elements movable radially to close in on the outside end of the headed container opposite said first-named die elements,

die projection means on said outer die elements to mate with the outwardly directed die recess means on said inner die elements, and means for operating the die elements against the edge of the head of a sheet metal container.

GEORGE M. AMBROSIUS.
